HUNTING BOOT PROTECTOR

Joe W. Graham, 622 E. Kelly St., Pharr, Tex., and Harold R. Graham, 514 N. 4th St., Uvalde, Tex.; said Harold R. Graham, assignor of forty percent to said Joe W. Graham, and of ten percent to Andrew J. Lidwin

Filed Aug. 17, 1961, Ser. No. 132,113

5 Claims. (Cl. 36—2)

This invention relates to new and useful improvements in leg protectors for safeguarding the legs and feet of hunters or other persons while walking through bushes, rocks, swamps and other areas harboring snakes.

In particular, the invention concerns itself with a leg or hunting boot protector of the type disclosed in our co-pending patent application serial No. 809,743, filed April 29, 1959, which has matured into Patent No. 3,003,261, granted October 10, 1961, of which this application is an improvement.

The principal object of the present invention is to structurally and functionally improve upon our earlier invention disclosed in the aforementioned co-pending application, the present invention being especially easy to apply and remove, comfortable to wear, and adaptable to very economical manufacture.

These together with other advantages and objects which will become subsequently apparent reside in the details of construction and operation as more fully hereinafter described and claimed, reference being had to the accompanying drawing forming a part hereof, wherein like numerals refer to like parts throughout, and in which:

FIGURE 1 is a side elevational view of the improved protector applied to the leg of a user;

FIGURE 2 is a rear elevational view thereof;

FIGURE 3 is an enlarged vertical sectional view, taken substantially in the plane of the line 3—3 in FIGURE 2;

FIGURE 4 is an enlarged horizontal sectional view, taken substantially in the plane of the line 4—4 in FIGURE 1; and

FIGURE 5 is a perspective view of the foot covering member of the protector.

Referring now to the accompanying drawings in detail, the improved protector is designated generally by the numeral 10 and consists of two main components, namely, a leg covering member 12 and a foot covering member 14.

The member 12 is of an open-ended, substantially tubular form and is provided with a longitudinal split at the back thereof, the split edges being undercut, forming recesses or undercut portions, and overlapped as indicated at 16. The member 12 is formed from suitable material such as resinous plastic, or the like, which is sufficiently rigid for the member to sustain its shape, yet is resiliently flexible enough to permit the member to be spread apart at the split edges 16 to facilitate its positioning on and removal from the leg 18 of the user. Keeper tabs 20 are provided integrally at one of the split edges 16 and overlap the other edge in order to maintain the split edges in alignment when the member is closed, and in addition, buckle-equipped straps 22 extend transversely of the split edges to retain the member in its closed position. Of course, upon separation of these buckle-equipped straps, opening of the leg member is facilitated.

The front upper portion of the leg member 12 is forwardly offset as indicated at 24 to provide clearance for the user's knee and an elastic band 26 is secured at the ends thereof as at 28 to the inside of the opposite side portions of the offset portion 24. The band 26 extends transversely in the portion 24 and engages the front of the knee in order to maintain the user's leg substantially centralized in the member 12. The rear upper portion

2

of the member 12 is provided with a recess 30 to afford clearance for the user's leg while stooping or sitting, as will be readily apparent. Finally, the inside of the lower end portion of the member 12 is provided at the back and partly around the sides thereof with a cushioning liner 32 to engage the heel portion of the user's hunting boot 34.

The foot covering member 14 is also formed from resinous plastic or other material capable of sustaining the shape of the member. As such, the member 14 is in the form of a cap which substantially conforms to and covers the upper of the boot 34, as illustrated. The interior of the member 14 is provided with a cushioning liner 36 to engage the upper of the boot and the top portion of the member 14 projects into the lower end portion of the leg member 12 when the members 12, 14, are assembled.

A substantially stiff but flexible tongue 38 is secured by suitable fasteners 40 to the inside of the lower front portion of the leg member 12 and is provided with snap fastener elements 42 for separable attachment to coating elements 44 on the foot member 14, the flexibility of the tongue 38 providing an articulated connection between the members 12, 14 to facilitate walking or other movement of the user's foot relative to the leg.

Apart from being connected to the member 12 by the tongue 38, the member 14 is also retained in position on the boot 34 by a plurality of straps, now to be described. A strap 46 extends under the shank of the boot and is adjustably connected by buckles 48 to a pair of strap members 50 secured to the opposite sides of the member 14. An elastic heel strap 51 is anchored at one end thereof as at 52 to one side of the member 14 and is provided at its other end with a hook 54 for adjustable engagement with apertures 56 formed in a complementary, but non-elastic strap 58 which is secured as at 60 to the relatively opposite side of the member 14. In addition, an elastic tensioning strap 62, provided intermediate its ends with a pad 64, engages the instep of the boot, the end portions of the strap 62 passing slidably outwardly through slots 66 formed in the side portions of the member 14 and being provided at their ends with hooks 68 which are adjustably engageable with apertures 70 to the member 14, as illustrated. The adjustable engagement of the hooks 68 in the apertures 70 affords an adjustment for tensioning the strap 62 against the instep of the boot, as will be apparent.

The foregoing is considered as illustrative only of the principles of the invention. Further, since numerous modifications and changes will readily occur to those skilled in the art, it is not desired to limit the invention to the exact construction and operation as shown and described, and all suitable modifications may be resorted to, falling within the scope of the invention as claimed.

55 What is claimed as new is:

1. In a protector, a boot covering member generally shaped so as to conform to the upper portion of a boot and including an upper portion and sides, a pair of slots through said sides, transverse rows of apertures through 60 said upper portion of the boot covering member adjacent and inwardly of said slots, a boot instep engaging and tensioning elastic strap having its intermediate portion disposed freely within the upper portion of said member and its end portions projecting slidably outwardly through said slots, and hooks provided at the ends of said strap, said hooks being selectively engageable with the apertures in said rows whereby to adjust the tensioning of said strap.

2. A protector comprising in combination a tubular leg enclosing member and a boot covering member, said members being substantially rigid and self-sustaining, said

boot covering member having an upper portion projecting into the lower end portion of said leg enclosing member and being movable relative thereto, and a substantially stiff but flexible tongue separably connecting said boot covering member solely to the front of the lower end portion of the leg enclosing member so as to provide a connection therebetween while allowing for a flexing in response to the movement of the wearer's foot relative to his leg, said tubular leg enclosing member being longitudinally split so as to form two separable longitudinal edges for facilitating its positioning on and removal from the leg of a wearer, a first undercut portion formed in the outer surface of said leg member along a first one of said edges, a second undercut portion formed in the inner surface of said leg member along the second one of said edges, said undercut portions receiving the opposite edges therein, tabs on said leg member projecting over the undercut portion along the first edge and maintaining the edges in alignment when the edges are received within the undercut portions, and means for releasably interconnecting said edges.

3. The device of claim 2 wherein said boot covering member upper portion is provided at opposite sides with a pair of slots and a transverse row of apertures adjacent to and inward of each slot, and a boot instep engaging and tensioning elastic strap having its intermediate portion disposed within the upper portion of the boot member and its end portions projecting slidably outwardly through said slots, and a hook provided at each end of said strap, both of said hooks being selectively engageable with the apertures in the rows whereby to adjust the tensioning of said strap.

4. A protector comprising in combination a tubular leg enclosing member and a boot covering member, said members being substantially rigid and self-sustaining, said boot covering member having an upper portion projecting into the lower end portion of said leg enclosing member and being movable relative thereto, and a substantially stiff but flexible tongue separably connecting said foot covering member solely to the front of the lower end portion of the leg enclosing member so as to provide a connection therebetween while allowing for a flexing in response to the movement of the wear's foot relative to his leg, said boot covering member upper portion being provided at opposite sides with a pair of slots and a transverse row of apertures adjacent to and inward of each slot, and a boot instep engaging and tensioning elastic strap having its intermediate portion disposed within the upper portion of the boot member and its end portions projecting slidably outwardly through said slots, 50

and a hook provided at each end of said strap, both of said hooks being selectively engageable with the apertures in the rows whereby to adjust the tensioning of said strap.

- 5 5. A protector comprising in combination a tubular leg surrounding member and a boot covering member, said members being substantially rigid and self-sustaining, said boot covering member having an upper portion projecting into the lower end portion of said leg surrounding member and being movable relative to the leg surrounding member within the lower end portion, and a flexible tongue separably connecting said boot covering member solely to the front of the lower end portion of the leg surrounding member so as to provide a connection therebetween while allowing for a flexing in response to the movement of the wearer's foot relative to his leg, said boot covering member upper portion being provided at opposite sides with a pair of slots and a transverse row of apertures adjacent to and inward of at least one of said slots, and a boot instep engaging and tensioning elastic strap having its intermediate portion disposed within the upper portion of the boot and its end portions projecting slidably outwardly through said slots, and a hook provided on at least one end of said strap, said hook being selectively engageable with the apertures whereby to adjust the tensioning of said strap, and means securing the other end of the strap to the boot covering member.
